DESIGN FOR A BICYCLE HUB
Walter F. Herold, Bridgeport, Conn., assignor to
The Bassick Company, Bridgeport, Conn., a
corporation of Connecticut
Application January 11, 1940, Serial No. 89,386
Term of patent 14 years

To all whom it may concern:
Be it known that I, Walter F. Herold, a citizen
of the United States, residing in Bridgeport, in
the county of Fairfield, State of Connecticut,
have invented a new, original, and ornamental
Design for a Bicycle Hub, of which the following
is a specification, reference being had to the accompanying
drawing, forming part thereof, in
which

Fig. 1 is an end elevation of a bicycle hub showing
my new design;
Fig. 2 is a side elevation of the same; and
Fig. 3 is a fragmentary sectional view of the
guard member.
I claim:
The ornamental design for a bicycle hub, sub-
stantially as shown. WALTER F. HEROLD.
